ELECTRIC ICE CRUSHER

Daniel E. McCue, Huntington Beach, Calif., assignor to
Rival Manufacturing Company, a corporation of
Missouri

Filed Feb. 12, 1968, Ser. No. 10,547

Term of patent 14 years

U.S. Cl. D89—1
Int. Cl. D7—05

Fig. 1.

Fig. 2.

Fig. 3.

Fig. 4.

Fig. 5.

FIG. 1 is a side perspective view of an electric ice crusher showing my new design;

FIG. 2 is a top plan view thereof;

FIG. 3 is a side elevational view thereof, taken from the side opposite that shown in FIG. 1;

FIG. 4 is a front elevational view thereof; and

FIG. 5 is a rear elevational view thereof.

I claim:

The ornamental design for an electric ice crusher, as shown.
